UNITED STATES PATENT OFFICE.

ALFRED FORNANDER, OF NEW YORK, N. Y.

SWEEPER.

1,182,547.

Specification of Letters Patent.

Patented May 9, 1916.

Application filed January 2, 1913. Serial No. 739,769.

To all whom it may concern:

Be it known that I, ALFRED FORNANDER, a subject of the King of Sweden, residing in the city of New York, borough of Manhattan, and county of New York, State of New York, have invented certain new and useful Improvements in Sweepers, of which the following is a full, clear, and exact description, which will enable others skilled in the art to which it pertains to make and use the same, reference being had to the accompanying drawings, and to the letters of reference marked thereon, which form a part of this specification.

15 The object of my invention is a sweeping device which will effectually remove and collect dust and dirt, and which is of simple construction, easy of manipulation, and of low cost of manufacture.

20 I make use of a casing provided with a dust pan and adapted to glide over the surface to be cleaned, and a revoluble brush, actuated solely by engagement of its bristles with said surface and so mounted within 25 said casing that its axis of rotation is immovable relatively to the edge of the dust pan, which is immediately adjacent the brush. By this arrangement, when pressure is applied by hand to the back of the casing, 30 such pressure performs two distinct offices, to wit, (1) it causes the said edge of the dust pan to hug tightly against the surface to be cleaned, and (2) it increases the degree of flexure of the brush bristles, and by so 35 doing renders more abrupt their release from such flexure, so that they exert considerable force in kicking the dust and dirt over the adjacent edge of the dust pan. Moreover, in moving the device over a spongy surface, 40 such as a carpet, rug or a garment, both of the offices just stated are attained in proximate proportion to the degree of pressure exerted upon the back of the casing. I find, also, that in this connection there is ad- 45 vantage in using a single dust pan, located to the rear of the brush, reckoned according to the general direction of travel of the sweeper over the surface to be cleaned.

That is to say, I find that there is advantage 50 in having the front portion of the casing open, or at least in having no obstruction, carried by the casing, in front of the brush. This arrangement enables the casing to be tilted slightly, if desired, in order that the 55 dust pan may sometimes be brought into more favorable position to receive the dirt

and dust, and that the degree of flexure of the bristles may be still further increased.

The apparatus of my invention is exceedingly cheap of manufacture, on account of its simplicity is not liable to get out of order, and possesses the practical advantages of being capable of removing and collecting both large and small articles from the fabric.

The device of my invention is well adapted for the removing of dirt, dust and other similar objectionable matters from any surface, whether of soft surfaces such as a woven fabric, or of hard surfaces such as asphalt, pavements, etc.

In the accompanying drawings, I illustrate one form of my device as applied to the removal of crumbs, dust and other loose material from a table-cloth, but I do not limit myself to this particular use for my invention.

Figure 1 illustrates an end view of one form of my device, partly broken away to show the dust-retaining receptacle. Fig. 2 illustrates a cross-section through the line X—Y of Fig. 1 also partly broken away.

A is a casing, the top portion C extending above and over the revoluble brush B and being bent forward so as to form the base plate D, the base plate being extended 85 forward toward the revoluble brush until closely approaching the bristles thereof, and then being extended backward and upward forming the front edge E of the dust-retaining receptacle L. The sides K, K are 90 attached to, or are extensions of, the top piece C, and are further attached to the base D in such a manner that the forward portion of the brush B will be exposed and uncovered. The brush B comprises resilient bristles attached to a double twisted wire core G supported by and revoluble 95 upon the two end bearings F, F.

H is a knob attached to the top of the casing and so situated as to cause a uniform firm pressure of the base D upon the surface over which the device is passed. The brush B is so situated as regards the base D, that the bristles will press upon the surface S over which the device is passed, and 105 will revolve when the sweeper is given a forward movement.

From the above description it is evident that the bristles of the brush will press upon the surface, forming a curve, as shown 110 in Fig. 1, and that when the device is pushed forward the friction of the brush upon the

surface will cause it to revolve, and that this forward movement will release the bristles from their bended position upon the surface, causing them to spring backward, thus 5 throwing the particles of dust and dirt backward into the dust-retaining receptacle L, with more or less violence and force.

It is thus seen, that the dust removing ability of the device does not depend upon 10 the action of a rapidly revolving brush which pulls or drags the dirt from the surface, but is caused by the snapping backward of the bristles of the brush, which receives its revolving motion directly from 15 the surface over which it passes, and which motion is not greater than that of the device itself.

The forward portion of the brush is exposed to allow it to collect large pieces of 20 material, and the lower portion is exposed to allow the bristles to come into contact with the surface over which the device is passed.

The complete exposure of the brush, at 25 the lower front end of the casing, also enables the flexure of the bristles to be increased, at the will of the operator, by slightly tilting the rear end of the casing upward, or even by applying a little more 30 pressure upon the front end of the casing than upon the rear end thereof. This is especially true where the surface to be cleaned is soft or spongy, as for instance a carpet, a rug or a garment.

35 The collected dirt may be readily removed by reversing the position of the sweeper, allowing it to fall out through the space between the brush and the top part of the casing.

40 I do not limit myself to the particular form, shape, size or arrangement of the various elements described above all of which can be varied without going beyond the scope of my invention as described and 45 claimed.

Having thus described my invention, what I claim is:—

1. In a device of the character described, the combination of a casing provided with a 50 dust pan and adapted to be glided over the surface to be cleaned, a revoluble brush so

journalized in said casing that a pressure upon the casing will force both dust pan and brush into closer engagement with the surface over which it is passed, said brush 55 having its axis of rotation immovable relatively to said dust pan and located adjacent one edge thereof, said brush being provided with bristles extending slightly away from said casing in order to engage the surface 60 to be cleaned, and thus to become flexed and released, throwing the dust backward into the dust pan, and also to turn said brush by direct pressure of said bristles upon said surface to be cleaned. 65

2. A device of the character described, comprising a casing provided with a dust pan and adapted to glide over a surface to be cleaned, a revoluble brush carried by said casing and actuated by direct pressure of 70 said brush upon said surface to be cleaned, the axis of rotation of said brush being immovable relatively to said dust pan, for the purpose of enabling pressure applied to the back of said casing, to force both said 75 dust pan and said brush into closer engagement with said surface to be cleaned, the brush possessing sufficient resiliency to throw the dust backward into said dust pan.

3. In a device of the character described, 80 the combination of a casing provided with a dust pan, a revoluble brush located upon one side of said dust pan, and actuated solely by its direct drag upon the surface to be cleaned, said brush being exposed upon 85 its side opposite said dust pan, and a pair of bearings secured rigidly to said casing and supporting said revoluble brush, for the purpose of rendering the axis of rotation of said brush immovable relatively to 90 said casing and said dust pan and so situated that a pressure upon the casing will force both the dust pan and the brush into closer engagement with the surface over which it is passed, the brush possessing sufficient 95 resiliency to throw the dust backward into the dust pan.

ALFRED FORNANDER.
